Atty.

UNITED STATES PATENT OFFICE.

PAUL HAUBNER, OF HELMSTEDT, GERMANY.

CAR DUMPER.

Application filed March 11, 1926, Serial No. 94,011, and in Germany February 11, 1925.

This invention relates to a new kind of car dumper in loop-shape for emptying cars. The improved loop-shaped car dumper works without driving mechanism and the 5 cars come out of the device at approximately the same level at which they have entered the same. There is no power required for emptying the cars nor for raising the same to the normal level. The cars form 10 in the loop a row in state of equilibrium. The equilibrium is upset if one or more cars following the one the other cause a displacement of the chain of cars standing on the loop-shaped trackway so that one or 15 more cars are forced out of the loop. The cars are held in the loop by means of top rails wherefrom results the most favorable stress for the car-frames. The trackway is first curved in downward direction and then 20 curved in upward direction.

The loop is preferably arranged in a vertical plane. The entrance may either be situated higher or lower than the exit, especially if the cars are conveyed to the loop-shaped dumper by an inclined track. The 25 platform of the car-dumper need have only two narrow apertures for the passage of the cars so that the installation of the car-dumper does not interfere with the bond of 30 the building. The cars stand buffer on buffer on the loop-shaped trackway; the entrance and exit of the cars is regulated so that bumping of the arriving car against the 35 cars standing on the trackway and oscillating of the outgoing cars is avoided.

The regulating chain for regulating the entrance and exit is conducted only over the entrance and over the exit approximately at car-height. The regulating chain will then 40 brake the cars immediately before getting onto the loop-shaped trackway and it will lift the outcoming car at uniform speed and prevent that it drop back if it has not yet got beyond the dead centre position. The 45 regulating chain must, if it is driven, move at slower speed than the conveying chain, for instance at half speed. Notwithstanding this the driving is very simple, and can be derived from the axle of the upper conveyor chain wheel.

An embodiment of the invention is shown,

by way of example, in the accompanying drawings in which—

Fig. 1 shows in elevation a car dumper having a regulating chain arranged above 55 the entrance and exit.

Fig. 2 is a plan view of Fig. 3.

The cars 2 coming in on the entrance track 1 have been released by the conveyer chain 3, for instance owing to the fact that 60 this chain is conducted at a slightly higher level. The cars come automatically into contact with the regulating chain 11, owing to the inclined track, this chain reducing the speed of the cars and conducting the same 65 slowly into the loop-shaped dumper. In the position 2^a the car is liberated by the regulating chain and runs a short distance down on the trackway to strike against the car in front, without however exerting a strong 70 shock. The contents of the car are emptied upon the shaking sieve 15 or into a bunker arranged underneath the dumper. The cars are held in the loop 5 by means of top rails 75 4. When the loaded car strikes against the last of the cars on the track way the row of cars is advanced and the front car is pushed up into such position that it is gripped by the regulating chain 11 and pulled out of the dumper in order to be conducted by a 80 slight incline onto the tracks 6 and 7 to the conveyer chain 11. The pulley 8 for changing the direction of the conveyer chain and the driving pulleys 10 for the regulating chain 11 are mounted on the same axle 9. 85 The direction of the regulating chain 11 is changed by the pulleys 12, 13, 13^a and 14 and it is conducted in such a manner that the entrance and exit of the loop-shaped dumper can be controlled at the same time 90 even if they are not directly the one at the side of the other. There might be however one regulating chain for the entrance and another for the exit. In this dumper the loop-shaped track way is situated in a vertical plane. This car-dumper works continuously, mainly by the impetus and gravity of the incoming cars which will generally be loaded, and wants only little driving 95 energy for the regulating chain.

I claim:—

1. A car-dumper for emptying cars, com-

prising a track way curved first in downward direction and then in upward direction and terminating at the height of the entrance, and top rails on this track way for holding the cars in the dumper, the cars standing in equilibrium on the curved track way in a row the buffers being in contact.

2. A car-dumper for emptying cars, comprising a track way curved first in downward direction and then in upward direction

and terminating at the height of the entrance, and top rails on this track way for holding the cars in the dumper, the cars standing in equilibrium on the track way in a row the buffers being in contact, and a ¹⁵ regulating chain conducted at car height over the entrance and exit.

In testimony whereof I affix my signature.

PAUL HAUBNER.
